ROBERT A. CHESEBROUGH, OF NEW YORK, N. Y.

Letters Patent No. 99,406; dated February 1, 1870; antedated January 24, 1870.

IMPROVED METHOD OF AERIAL TRANSIT.

The Schedule referred to in these Letters Patent and making part of the same

To whom it may concern:

Be it known that I, ROBERT A. CHESEBROUGH, of the city, county, and State of New York, have invented a new and useful Method of "Aerial Transit;" and I, hereby declare the following to be a full, clear, and exact description thereof, which will enable those skilled in the art to make and use the same, reference being had to the accompanying drawings, which form part of this specification.

The purpose of this invention is to supply the means of rapid transit across rivers, or from place to place on the land, for passengers, express matter, and the mails, and the method of accomplishing this purpose is by stretching a cable from one tower, or high building, across the river or land it is desired to cross, to another building or tower, of equal height, at the other end of the route. The ends of this cable are not fastened at equal distances from the tops of both towers, but one end of the cable is fastened at or near the top of one tower, and the other end of the cable at a point considerably below the top of the other tower, so that the cable presents a decided incline along almost its entire length. A light car or coach being suspended by wheels from the cable, and starting from the first tower, will run down the inclined cable to the other tower by its own gravity. A second cable is attached to the top of the second tower, and forms a similar incline, connecting with the first tower, by which the car may return, thus establishing continuity of travel. The car, on arrival, is detached from the foot of the first incline, and elevated to the summit of the return incline, and there attached to the second cable.

Narrow streams or rivers have heretofore been crossed by means of a basket or light car suspended from a cable, the said car being drawn across, from bank to bank of the stream, by means of a rope and windlass; but my improvement differs essentially from this, inasmuch as my cables are inclined and my coaches run by their own gravity, traction-ropes being entirely dispensed with, and the amount of height lost in the decline is compensated by elevating the coach, on arrival, an equal distance to the head of the return incline.

The principle applied in this improvement is the same as that described in my patent for an "elevated railway," No. 79,952, dated July 14, 1868.

Having thus explained the general character of my invention, the following brief description, with reference to the accompanying drawings, will show how the same is or may be carried into effect.

Figure 1 represents two towers on opposite banks of a river, from which two inclined cables are suspended.

Figure 2, a side view of a coach or car.

Figure 3, an end view of a coach or car.

We will suppose the two towers A to be each one hundred and twenty feet in height, situated on the

opposite banks, B, of a navigable river, C, one quarter of a mile wide.

From these two towers, two cables, D and E, are stretched, the lowest point of each being, say, one hundred feet above high-water mark, to enable vessels with high masts to pass thereunder.

At the tops of the towers, in the sides turned toward each other, are two openings or ports, F, G; H, and I, one being fifteen feet lower than the other, not being placed beneath it, but to one side, in order that the cars may freely pass without touching each other.

The cable D issues out at the top of the opening F, extends across the river, and enters the opening I in the opposite tower, thus forming a decline of fifteen feet in the quarter of a mile, without reference to the deflection of the cable.

The cable E in the same manner connects the port H in one tower, with the port G in the other tower, thus forming a similar decline in reverse order. The ends of the cables are securely fastened in the interiors of the towers, after entering at the ports, allowing room below the tops of the ports to let the wheels of the coaches pass without touching. The ports are made sufficiently large to allow the coaches to enter and leave freely.

An elevator is placed in the top of each tower, to convey the coaches from the lower ports to the upper ones. Its position is on the inside of the tower, and is shown by the red lines at K.

The operation is as follows:

A coach being attached to the cable E, inside the port H, runs out and down the decline over the river into the port G. It is then detached from the cable E, placed on the elevator, hoisted fifteen feet, attached to the cable D, issues from the port F, runs back over the river, and enters the port I, where it is again detached and elevated, and so on.

Passengers enter the towers at the door, as shown in the drawing, and either walk up spiral staircases to where the coaches are situated, or may be elevated by elevators working up and down on the inside of the towers.

The towers may be substantially built of either wood, stone, or iron, and may be rendered more secure by being braced to the ground by iron rods, running in a direction opposite to that of the cables, thus relieving the tower of the side-strain on them caused by the weight of the cables and coaches.

The cables should be made of steel wire, of an inch or more in diameter, with the surface made perfectly even for the wheels to run upon.

The line that a suspended cable of this length would take, (one end being fifteen feet higher than the other,) would be such as to place the lowest point of deflection quite near the lower end of the cable.

For the sake of illustration, let us suppose the lowest point of deflection on cable D to be at J, and twenty feet below its highest end; there will then be a descent of twenty feet for the car to run down, in which it will acquire speed enough to overcome the ascent of five feet from the lowest point to port I.

If it shall be found, in practice, that a descent of fifteen feet to a quarter of a mile is not sufficient, it may be made greater; or, if too much, it may be reduced. No accurate rule can be here laid down, as I am not now prepared to state the least amount of deflection necessary to a cable of this length and character. The object will, of course, be to run the cables as nearly in a straight line as may be, without adding strain to their actual weight.

The coach or car is shown in fig. 2. It consists of a light iron box, N, suspended by strong iron bands, O, from two wheels, P, deeply grooved, which run on the cable as on a track, the weight of the car below the wheels serving to keep the wheels in an upright position on the cable.

In order to attach and detach the car to and from the cable, the iron bands on one side of the car, just below the wheels, are provided with openings and covers for the openings R, which have strong hinges at one end and fastenings at the other, so that they may be either opened or shut, and fastened securely. They are shown as shut in fig. 2, and as open in fig. 3.

It will be seen that to detach a car it has to be raised high enough to clear the wheels from the cable, and bring the cable on a level with the openings. By then undoing the fastenings and raising the hinged covers R, the car can, by a side movement, be quickly detached from the cable. The red line in fig. 2, and the red dot in fig. 3, show the cable and its position as regards the car.

The car is provided with brakes S S, to restrain its speed when nearing the tower, and finally stop it on arrival therein, and a rope to operate the brakes can be introduced into the car.

The coaches can be made to contain from six to twenty passengers, or even more, the limit only being determined by the strength of the cables and the stability of the towers.

As the mechanic, by observing the drawing, will readily understand the construction of the car, and as the same may be varied, it will not be necessary to enter upon a more detailed explanation.

The diameter of the wheels may vary from one to two feet. It is not necessary that the coaches should be placed immediately beneath the wheels. They may be suspended therefrom by means of long iron rods,

allowing the coach to almost skim the water, while the wheel-truck runs on the cable far overhead.

This mode of transit may be used on land, between place and place, and, when so used, the height of the towers may be much less than when crossing a navigable river, in fact, in some places and for some purposes the towers might not need to be over twenty feet high.

I do not limit myself to the distance between the towers, or to the number of towers, as it is plain that several may be placed at different points, and communicate with each other in the manner already herein shown; or a large central tower may be placed on a central position, and several sets of cables may radiate therefrom to various other towers.

Instead of one cable being used, on which the car runs, two cables may be substituted, running side by side. Each car will then have four wheels, two of which will run on each cable.

Instead of running the car on the cables, two cables may be used to sustain an ordinary railroad-track, forming a uniform or properly-graduated incline the whole distance. In this case the two rails of the track are firmly braced together, and rest on a system of girders which form a complete frame-work, which should be fastened to the cables by multitudinous steel wires, thus forming a roadway on which small cars, of the ordinary pattern, may be run.

That the method of "aerial transit," herein shown, may be made perfectly safe, seems as undeniable as that long bridges, sustaining enormous weight, are upheld by cables from towers on opposite banks of rivers.

I can see no reason why a cable might not be stretched over a river a mile wide, and operated satisfactorily, if it can be made sufficiently strong, which can scarcely be doubted, and in this way communication be maintained across wide rivers at a high speed.

What I claim as my invention, and desire to secure by Letters Patent, is—

1. A method of aerial transit composed of two cables, inclined in opposite directions, arranged substantially as herein shown, on which coaches suspended therefrom may run in either direction by their own gravity.

2. The combination of the towers or buildings A, the inclined cables D and E, the elevators K, and the coach L, all operating substantially as described.
